UNITED STATES PATENT OFFICE.

JAMES LAMB, OF CANTON, ILLINOIS.

TELpherage System.

1,166,227.

Specification of Letters Patent. Patented Dec. 28, 1915.

Application filed April 27, 1915. Serial No. 24,299.

To all whom it may concern:

Be it known that I, JAMES LAMB, a citizen of the United States of America, residing at Canton, in the county of Fulton and State of Illinois, have invented new and useful Improvements in Telpherage Systems, of which the following is a specification.

In carrying out the present invention, it is my purpose to provide a system of telpherage which will be found especially useful in post offices for carrying mail from one point to another; department stores for transporting merchandise and other articles from place to place; and analogous places, and wherein the flow of current to the motor of the electrically propelled vehicle may be cut off and the vehicle brought to a stop quickly and conveniently so that the operator may fill the carrier with the goods to be transported.

It is also my purpose to improve and simplify the general construction of telpherage apparatus and to provide apparatus of the class described which may be installed and maintained at a minimum expense and which will operate efficiently and effectively under all conditions.

With the above and other objects in view, the invention consists in the construction, combination and arrangement of parts hereinafter set forth in and falling within the scope of the claims.

In the accompanying drawings: Figure 1 is a view in side elevation of a telpherage system constructed in accordance with the present invention, two termini and the trackway between the same being shown. Fig. 2 is a top plan view of the same. Fig. 3 is an enlarged vertical sectional view through one of the termini. Fig. 4 is a horizontal sectional view therethrough. Fig. 5 is a view of a detail of the invention.

Referring now to the drawings in detail, 1, 1 designate the termini of a system of telpherage, while 2 indicates a trackway spanning the space between the termini 1, 1. Each terminus comprises a base 3 and a supporting frame 4 uprising from the base 3. The upper end of the supporting frame 4 receives and supports the adjacent extremity of the trackway 2 and this trackway 2 embodies parallel lines of rails 5 spaced apart a suitable distance.

6 designates a wheeled carrier comprising a supporting frame 7 equipped, with axles

respectively upon the outer ends of which are mounted wheels 8 engaging the lines of rails 5 of the trackway. Secured to the frame 7 and depending therefrom between the lines of rails of the trackway 2 is a basket 9 or other form of container. Mounted upon the frame 7 and suitably secured thereto is an electric motor 10 and fixed upon the shaft of the motor is a worm 11 meshing with a worm wheel 12 keyed upon one end of a drive shaft 13, such shaft having the remaining end thereof connected in driving engagement with one of the axles of the carrier. Secured to the frame 7 and projecting laterally therefrom is an arm 14 formed of hinged sections, as shown in Fig. 5, and having the outer section thereof formed with a vertical bore and arranged within this bore is a stem 15. To the lower end of the stem 15 is fastened a yoke 17 and journaled within the yoke is a trolley wheel 18. This stem is slidably mounted within the bore and the upper end thereof is equipped with a head 19, while encircling the lower portion of the stem 16 between the under surface of the arm and the yoke 17 is a coiled expansion spring 20 acting to hold the stem normally at its limit of downward movement and the head 19 in engagement with the upper surface of the arm.

Extending longitudinally of the trackway 2 is an electric current carrying conductor 21 to which and one of the lines of rails of the trackway are connected, respectively, the terminals of a suitable source of electrical energy. The trolley wheel 18 bears upon the conductor 21 and is connected with one terminal of the motor, while the remaining terminal of the motor is grounded upon one of the wheels 8 bearing upon the particular line of rails connected with the generator. Thus, as long as the trolley wheel is in engagement with the trolley wire, current is fed to the motor 10 with the effect to rotate the worm 11, worm gear 12 and shaft 13 and so propel the carrier over the lines of rails 5 of the trackway. Pivoted upon each base 3 is a foot treadle 22 connected through the medium of a chain 23 with the upper extremity of a vertical lever 24 pivoted upon the base 3. Extending rearwardly from the lever 24 is a link 25 connected with the upper end of an arm 26 uprising from one end of a horizontal shaft 27 journaled in alining bearings carried by the base 3. The remaining extremity of the shaft 27 is formed with

a rearwardly projecting arm 28 and connected with the rear end of the arm 28 is the lower end of a vertical rod 29. Secured to the rod 29 and arranged longitudinally 5 thereof is a horizontal strip 30 of wood or other material having the upper end edge thereof disposed in proximity to one of the trolley wires 21. The upper edge of the strip 30 is formed with a groove 31 adapted 10 to receive the trolley wheel journaled in the yoke carried by the movable stem 16, and a relatively small groove 32 contiguous to the bottom wall of the groove 31 adapted to receive the trolley wire 21 upon which said 15 movable trolley wheel bears.

33 designates a retractile spring having one end connected to the rear extremity of the link 25 and the opposite end secured to the base 3.

20 In practice, when it is desired to check the carrier the treadle 22 is depressed, thereby pulling the chain 23 and swinging the lever 24 about its pivotal connection with the base 3. In the swinging of the lever 24 the link 25 pulls the arm 26 against the action of the spring 33 and so rocks the horizontal shaft 27 with the effect to elevate the arm 28, rod 29 and strip 30. In the upward movement 25 of the strip 30 the groove 32 in the upper edge thereof receives the trolley wire 21 while the groove 31 receives the trolley wheel carried by the movable stem 16 and in the continued upward movement of the strip, the longitudinal wheel on the stem 16 30 is elevated against the action of the spring 20, thereby disengaging said wheel from the wire 21 and stopping the carrier, the groove 31 acting as a brake to check the momentum of the carrier when the current is cut off 35 from the motor.

From the foregoing description taken in connection with the accompanying drawings, the construction, mode of operation and manner of employing my improved system 40 of telpherage will be readily apparent. It will be seen that I have provided a telpherage system whereby a trolley wheel on the carrier and engaging one of the current conductors may be moved out of engagement 45 with such conductor and simultaneously braked so as to cut off the propelling power of the motor and check the speed of the carrier.

50 While I have herein shown and described the preferred form of my invention by way of illustration, I wish it to be understood that I do not limit or confine myself to the precise details of construction herein described and delineated, as modification and variation may be made within the scope of the claims without departing from the spirit 55 of the invention.

I claim:

60 1. In a telpherage system, a trackway, a wheeled carrier on said trackway, a motor 65

for propelling said carrier, an electric current carrying conductor extending along the trackway, a trolley wheel on said carrier engaging said conductor and connected to said motor and capable of movement out of engagement with said conductor, a horizontal strip having the upper edge thereof formed with a groove adapted to receive said trolley wheel and a groove contiguous to the inner wall of said first groove adapted to receive 70 said trolley wire, and means for moving said strip vertically to engage said trolley wheel and wire in the respective grooves and so disengage the trolley wheel from the wire. 75

2. In a telpherage system, a trackway, a wheeled carrier on said trackway, a motor 80 for propelling said carrier, an electric current carrying conductor extending along the trackway, a trolley wheel on said carrier engaging said conductor and connected to said motor and capable of movement out of engagement with said conductor, a horizontal strip having the upper edge thereof formed with a groove adapted to receive said trolley wheel and a groove contiguous to the inner 85 wall of said first groove adapted to receive said trolley wire, a treadle, a connection between said treadle and strip whereby the latter will be moved upwardly in the downward movement of the treadle to engage 90 said trolley wheel and wire in the respective grooves whereby the trolley wheel will be disengaged from the wire, and a spring for restoring said strip to normal position succeeding the release of said treadle. 95

3. In a telpherage system, a trackway, a wheeled carrier on said trackway, a motor on said carrier, driving connections between said motor and certain of the wheels of the carrier, an electric current carrying conductor extending longitudinally of the trackway and spaced apart therefrom, a block extending laterally from the carrier, a vertical stem carried by said block, a trolley wheel on the lower end of said stem engaging said 105 conductor, and connections between the respective sides of the motor and said conductor and trackway. 110

4. In a telpherage system, a trackway, a wheeled carrier on said trackway, a motor on said carrier, driving connections between said motor and certain of the wheels of the carrier, an electric current carrying conductor extending longitudinally of the trackway and spaced apart therefrom, a block extending laterally from the carrier, a vertical stem carried by said block, a trolley wheel on the lower end of said stem engaging said conductor, connections between the respective sides of the motor and said conductor and trackway, and means for moving said trolley wheel out of engagement with said conductor to cut off the flow of current to the motor. 115

5. In a telpherage system, a trackway, a 120

wheeled carrier on said trackway, a motor on said carrier, driving connections between said motor and certain of the wheels of the carrier, an electric current carrying conductor extending longitudinally of the trackway and spaced apart therefrom, a block extending laterally from the carrier, a vertical stem carried by said block, a trolley wheel on the lower end of said stem engaging said conductor, connections between the respective sides of the motor and said con-

ductor and trackway, and foot operated means for moving said trolley wheel out of engagement with the conductor to cut off the flow of current to the motor. 15

In testimony whereof I affix my signature in presence of two witnesses.

JAMES LAMB.
